(57) **CLAIM**

The ornamental design for a set of headlights for vehicles as shown and described.

DESCRIPTION

1. Set of headlights for vehicles

1.1: Perspective view;

1.2: Front view;

1.3: Back view;

1.4: Left view;

1.5: Right view;

1.6: Top view;

1.7: Bottom view;

1.8: Perspective view of part 1;

1.9: Front view of part 1;

1.10: Back view of part 1;

1.11: Left view of part 1;

1.12: Right view of part 1;

1.13: Top view of part 1;

1.14: Bottom view of part 1;

1.15: Perspective view of part 2;

1.16: Front view of part 2;

1.17: Back view of part 2;

1.18: Left view of part 2;

1.19: Right view of part 2;

1.20: Top view of part 2; and

1.21: Bottom view of part 2.

This design product is a set, and there is no direct physical connection relationship between the components, but they are intended to be used in combination.

1 Claim, 21 Drawing Sheets
